United States Patent Office

Des. 180,166
Patented Apr. 23, 1957

180,166

CASE FOR A FILM PROJECTOR OR SIMILAR ARTICLE

Francis D. Wagner, Kansas City, Kans., assignor to Perceptual Development Laboratories, Incorporated, Clayton, Mo., a corporation of Missouri

Application November 10, 1955, Serial No. 38,858

Term of patent 14 years

(Cl. D61—1)

Fig. 1

Fig. 3

Fig. 1 is a plan view of a case for a film projector or similar article, showing my new design;

Fig. 2 is a side elevational view thereof; and

Fig. 3 is an end elevational view thereof.

I claim:

The ornamental design for a case for a film projector or similar article, substantially as shown.
